UNITED STATES PATENT OFFICE.

LOUIS YAGODA, OF NEW YORK, N. Y.

DOLL-EYE MOUNTING.

Application filed April 24, 1925. Serial No. 25,534.

This invention relates to dolls, and particularly to the construction of movable eyes for said dolls.

In doll heads of small sizes, it has heretofore been customary to cut off the top of the head in order to provide access to the interior of the head for securing the eyes in place. My invention contemplates the assembly of the eyes through the neck of doll heads of any of the usual and even small sizes and contemplates further a simplified construction whereby the manufacturing cost and the cost of production of the eyes are both considerably lessened as compared with the present types without in any way detracting from the efficiency of the operation of said eyes.

The various objects of my invention will be clear from the description and illustration 20 of the preferred embodiments of my invention shown in the drawings, in which,—

Fig. 1 is a central vertical section of a doll head showing the eyeballs in the open or "awake" position thereof.

Fig. 2 is a similar section on the line 2—2 of Fig. 1.

Fig. 3 is a vertical section on the line 3—3 of Fig. 2 showing the head turned into the "asleep" position of the doll, and showing 30 the eyeballs in the closed position thereof.

Fig. 4 is a perspective view of my improved eyeball unit.

Fig. 5 is a vertical central section of the doll head showing a modified form of mounting for the eyeball unit, and

Fig. 6 is a horizontal section of the same taken on the line 6—6 of Fig. 5.

In that embodiment of my invention illustrated in Figs. 1, 2 and 3, a preferably central extension or bridge 10 is molded, cast, or pressed so as to project inwardly on the inside of the doll head preferably midway between the eyeball sockets 11. While said bridge 10 is made preferably integral with the remainder of the head, it will be understood that said bridge or extension may be made of a separate piece suitably secured in place. The horizontal width of said bridge 10 between the eye sockets is sufficient to provide a bearing of the desired length for the eyeball connecting and operating shaft 12, as will more clearly be pointed out hereinafter. In said bridge 10, a horizontally disposed groove 13, the height and depth of which is preferably substantially the same as the diameter of said shaft is made to extend

inwardly from the vertical inner face 14, said groove being open at said face for the easy insertion of the shaft 12 thereinto. The horizontal disposition of the groove makes it possible to pass the shaft 12 with the eyeballs 15 secured thereto up through the neck and through the open end of the groove into place in a single movement with ease and certainty. Said open end of the groove 13 may be closed in any suitable manner after the shaft has been inserted thereinto for preventing said shaft 12 from slipping out of the groove 13. For this purpose I have illustrated a wooden block 30, adapted to be glued or otherwise secured to the inner surface 14 of the bridge 10. I have found that the sockets 11 are sufficient to prevent displacement of the eyeballs after the shaft 12 is sealed in the groove therefor. For causing the eyeballs 15 and the shaft 12 connecting said eyeballs to rotate in their sockets 11 and in the groove 13 respectively, I provide a preferably U-shaped member 16 preferably of a single integral piece of material, connected to the shaft 12 in any suitable manner as by means of the screws 17. In order to cause said member 16 to serve as a weight to rotate the eyeballs and to further serve as a stop to limit the rotation of said eyeballs in either direction, I prefer to fasten said member 16 to the shaft 12 near the upper ends 18 thereof, the lower portion 19 thereof having sufficient leverage to turn the shaft 12 on the rotation of the head as will be more fully described hereinafter. Contact of said ends 18 with the inside of the doll head stops the rotation of the shaft 12 and the eyeballs carried thereby in one direction, the rounded end 19 of said member serving as a stop to limit the rotation of the eyes in the opposite direction by the engagement thereof with a portion 20 of the bridge 10, or by the engagement thereof with any other part of the inside surface of the doll head.

To assemble my improved device, the eyeball unit 31 is passed up through the neck opening 21 of the doll head and the shaft 12 inserted in the groove 13. One face of the securing member 30 having first been covered with cementing material of any desired nature, such as ordinary glue, said member is then pressed into contact with the flat inner surface 14 of the bridge 10, whereby the open end of the groove 13 is completely sealed and closed, and the shaft 12

secured permanently in properly aligned position, with the eyeballs fitting into and maintained in place by the sockets 11. It will be seen that even though the opening 21 is barely of sufficient size to permit the entrance only of the eyeball unit 31 and one finger of the operator, it is a simple matter to slip the bar 12 into position in the groove and then to insert the member 30 thereover. It will further be seen that this operation may be carried out in a single movement rapidly and effectively by unskilled labor without the necessity for cutting open the doll head or for otherwise injuring said head, and that the expense of assembly is thereby considerably reduced over the present methods.

In that modification of my invention shown in Figs. 5 and 6 the groove 13 in the bridge 10 is dispensed with and said bridge made considerably smaller, so that it may project into the interior of the head a comparatively short distance. It will be understood, however, that said bridge may be entirely dispensed with, if desired, and a projection substituted therefor by gluing or otherwise attaching a wooden, composition or other strip of the proper size at the proper point on the inside of said head between the eye sockets 11. In this form of my invention, the shaft 12 is maintained in position by means of the cross bar 22, in one end of which is cut the preferably horizontal groove 23 and the other end 24 of which passes through a suitable opening 25 in the doll head, and is bevelled and finished off to correspond with the outer contour of said head. A suitable groove as 26 preferably of the cross sectional size and shape of the cross bar 22 may be made in the bridge 10 or in the piece substituted therefor, so that the grooved end of said cross bar may be glued or otherwise quickly fastened in said groove 26. For assembling this form of my improved mounting the eyeball unit 31 is passed up through the neckhole 21 as hereinbefore described, the eyes being placed into the sockets in suitable alignment and registration. The cross bar 22 is then passed through the opening 25 until the groove 23 is engaged by the shaft 12 and the end 27 thereof enters and is secured in the groove 26, it being understood that the cementing material has first been placed on the ends 27 and 24. Said cross rod 22 is pushed into said groove 26 as far as possible or until the shaft 12 reaches the innermost end of the groove 23.

It will be seen that when my improved mounting is assembled, one element of the cylindrical shaft 12 contacts with the inner surface 14 of the bridge 10, and the diametrically opposite element of said shaft contacts with the innermost part of the groove 23, whereby said shaft 12 is securely sup-

ported for its rotative movement. It will further be seen that by making the grooves 13 and 23 horizontal, the shaft 12 may be quickly and easily slipped into position by a movement substantially at right angles to that necessary to insert the eyeball unit into the doll head, thereby making the assembly operation quick and certain. It will further be seen that my device is simple and inexpensive to manufacture, that it is durable and not likely to get out of order, and is well adapted for commercial production on a large scale.

I claim:

1. In a doll head having eye sockets therein, a pair of eyeballs arranged in said sockets, a straight one piece horizontal shaft joining said eyeballs, a U-shaped member of a single piece of material of substantially uniform cross-section throughout secured tangentially near the upper ends thereof to said shaft at points near the center of said eye-balls and a bridge formed integrally with and continuous with the inner surface of said head in spaced relation to the ends of said U-shaped member and projecting inwardly of said head between said eye sockets and having a horizontal groove therein for holding said shaft rotatably in place, and in which said shaft may be placed by the insertion thereof through the neck of said head.

2. In a doll head having eye sockets therein, a pair of eyeballs, a straight, one-piece horizontal shaft joining said eyeballs and adapted to be arranged in place in one operation through the neck of said head, a horizontally grooved projection extending from and integral with said head adapted to receive said shaft, a flat, substantially rectangular face lying in a vertical plane on the inner surface of said projection, a rectangular prismatic member of substantially the same size as said face secured to said face in substantial registration therewith for maintaining said shaft in operative position in the groove of said projection, and weighty means extending slightly above said eyeballs and below the bottom edge of said projection secured to said shaft in spaced relation to said projection.

3. In a doll head having eye sockets therein, a bridge formed integrally with and of the same material as said head terminating in a substantially vertical plane inner face and extending inwardly of said head, and having a groove extending horizontally therein from said inner face, eyeballs in said sockets, a straight one-piece shaft secured to said eyeballs across the centers thereof and adapted to enter said groove to a point at which the outermost element thereof lies in substantially the same plane as said inner face, a member having a flat outer surface secured to said inner face for preventing said

- shaft from leaving and from displacement in said groove, and a single piece of bent wire secured to said shaft in spaced relation to said bridge and serving as a weight for moving said shaft and as a stop for limiting the rotation of said shaft.
4. In a doll head having eye sockets therein, a bridge formed integrally with and of the same material as said head terminating in a substantially vertical inner face continuous with the inner wall of said head and having a groove extending horizontally therein from said face, a straight horizontal shaft adapted to enter said groove to a point at which the outermost element thereof lies in substantially the same plane as said inner face of said bridge, means secured to said inner face for preventing said shaft from leaving said groove, and a U-shaped member of a single piece of material of the same cross sectional size and shape throughout secured to said shaft near the upper ends thereof and adapted to rotate said shaft on the rotation of said head and to limit the rotatable movement of said shaft by the alternate engagement of the upper and lower ends thereof with the inner surface of said head respectively.
5. In a doll head having eye sockets therein, a horizontal eyeball carrying shaft, means securable to the inner surface of said head for rotatably maintaining said shaft in place, a combined stop and weight member consisting solely of a single piece of heavy wire circular in section, bent into U-form and secured to said shaft, near the ends of said shaft, an upper portion on said member projecting slightly above said shaft and adapted to engage the inner face of said head for limiting the rotation of said shaft in one direction, and a lower portion of said member adapted to rotate said shaft by the weight thereof on the rotation of said head and further adapted to engage the inner face of said head for limiting the rotation of said shaft in the opposite direction.
6. In a doll head having eye sockets therein, an eyeball carrying shaft, means having a horizontal groove therein closed at the top and bottom and at one side thereof supporting said shaft in said groove, means for closing the open side of said groove for preventing said shaft from leaving said groove, and a combined stop and weight member of a single piece of wire of circular cross section throughout bent into a U-form, secured above the center thereof to said shaft, near the ends of said shaft for rotating said shaft on the rotation of said head and for limiting the rotation of said shaft in either direction.
7. In a doll head having eye sockets therein, a bearing, a straight horizontal eyeball carrying shaft in said bearing, and a member of a single piece of heavy wire of circular cross section and bent into substantially upright sides with a substantially semi-circular bend joining said sides and secured above the center thereof to said shaft for rotating said shaft on the rotation of said head and for limiting the rotation of said shaft in either direction.
8. In a doll head having eye sockets therein in a pair of eyeballs arranged in said sockets and held against transverse movement thereby, a bridge extending inwardly of said head between said eye sockets, terminating in a vertical rectangular flat inner face lying in a single plane and continuous with the inner wall of said head, and having a groove extending horizontally therein from the said face, said groove being closed at the top and bottom, and at one side thereof, and open at said vertical face, a horizontal shaft connecting said eyeballs, adapted to substantially fill said groove, and adapted to be arranged in place in said groove through the neck of said head in one operation, a rectangular prismatic member having a face of substantially the same size and shape as said inner face securable to said vertical inner face in substantial registration therewith adapted to close the open side of said groove for preventing said shaft from leaving said groove and a U-shaped combined stop and weight member of a single piece of heavy wire secured near the upper end thereof to said shaft for rotating said shaft on the rotation of said head, and for limiting the rotation of said shaft in either direction by the alternate engagement of the upper and lower ends of said U-shaped member with the inner surface of said head.
9. A combined stop and weight member for an eyeball unit, comprising a single piece of heavy wire of substantially circular cross section throughout, bent to form a pair of substantially parallel arms, and a circular bend joining said arms, and means for securing said arms tangentially to said unit at a point near the ends of said arms and said unit, and where said arms meet said unit.
10. An eye unit for a doll head comprising a pair of hemi-spherical eyeballs, a straight shaft joining said eyeballs, a U-shaped unitary member of a single piece of material of circular cross-section throughout, and having a pair of substantially upright arms and a semi-circular bend joining said arms and a pair of screws passing through said arms near the ends thereof and into said shaft near the centers of the respective eyeballs.

LOUIS YAGODA.
